HANS VIDEBAK, OF CALGARY, ALBERTA, CANADA, ASSIGNOR OF ONE-HALF TO NIELS P. P. PALLESON, OF CALGARY, ALBERTA, CANADA.

AUTOMATIC AIR AND STEAM COUPLING ATTACHMENT FOR RAILWAY-CARS.

1,084,586.

Specification of Letters Patent.

Patented Jan. 13, 1914.

Application filed March 22, 1913. Serial No. 756,126.

To all whom it may concern:

Be it known that I, HANS VIDEBAK, a subject of the King of Great Britain, and resident of the city of Calgary, Province of Alberta, Canada, have invented certain new and useful Improvements in Automatic Air and Steam Coupler Attachments for Railway-Cars, of which the following is a specification.

10 The invention relates to improvements in devices for automatically coupling air or steam conduit lines between railway cars, as described in the present specification, and illustrated in the accompanying drawings 15 that form part of the same.

The invention consists essentially of the novel arrangement and construction of parts, whereby each coupling member is springheld to an outward angular position, 20 and fitted with a tapered forward portion and a socket adapted to co-act when meeting a second coupling member, and place in register suitable valve controlled openings to complete a train-line conduit.

25 The objects of the invention are to provide a means of a simple and durable construction, whereby the train-line conduit of a railway train may be automatically coupled coincidently with the meeting and coupling of the cars, and thus eliminate the necessity of attendants entering between the cars to couple the train-line connections by hand with the resultant labor and danger to life.

30 In the drawings, Figure 1 is a side elevation view of a pair of the automatic couplers in readiness to meet and attached to the regular couplers of the cars. Fig. 2 is a plan view of a pair of couplers when 35 in register, showing the position of the regular couplers thereabove in dotted lines. Fig. 3 is an enlarged plan view of a coupler. Fig. 4 is an enlarged side elevation view of a coupler. Fig. 5 is a plan sectional view on the line A—B in Fig. 4. Fig. 6 is an enlarged perspective view of 40 the coupler with the solid front portion thereof broken away to show the arrangement of the parts in the interior thereof.

45 50 Like numerals of reference indicate corresponding parts in each figure.

Referring to the drawings, 1 is the regular car coupling of any standard design, having the knuckle pin 2 thereof elongated and ex-

tending a considerable distance below the 55 coupling 1 as shown in Fig. 1, to accommodate and support the automatic air-line coupling as hereinafter described, said pin having the head at the bottom thereof, and the upper end held in the coupler by the washer 60 and split pin 10.

3 is a groove extending longitudinally of the knuckle pin 2 toward the lower end thereof, and having the radially extending recesses 4 at each end thereof to receive the 65 ends of a staple, as hereinafter described.

5 is the body of the air-line coupler formed substantially rectangular, and having the front face 6 thereof angularly offset at 7 toward the forward end, and the 70 tapered extension 8 forming a horn or beak similar to an anvil beak, and forming the forward end.

9 is a slot extending vertically through the body of the coupler, and through which the 75 lower end of the pin 2 extends to support the air coupler, which normally rests upon the head as arranged at the lower end of the pin.

11 is an opening through the rear end of 80 the coupler into the slot 9.

12 is a recess in the bottom of the coupler, forming a chamber for certain operative parts as hereinafter described.

13 is a cored passage extending from the 85 angular front face 7 of the coupler through to the back thereof, said cored passage being situated above the recess 12 and ahead of the vertically extending slot 9.

14 are orifices extending from the vertical 90 slot 9 to the forward end of the coupler, one above and one below the cored passage 13, said orifices being counter-bored at the inner ends thereof at 15 for substantially one-half the length. 95

16 is an arc-shaped plate having the inner face thereof formed to fit the periphery of the pin 2 for substantially halfway therearound, said plate bearing against said pin within the vertical slot 9. 100

17 are guide rods securely riveted at the inner ends thereof in suitable orifices in the plate 16, and extending outwardly therefrom into the orifices 14 in said coupler.

18 are spiral springs encircling the rods 105 17 between the plate 16 and the outer end of the counter-bored portions 15 of the orifices 14, said springs exerting a continual

pressure upon the plate 16, and thereby retaining the pin 2 normally at the end of the vertical slot 9 adjacent the inner end of the coupler, though allowing the coupler to move against the action of the springs to the extent of the length of the slot 9 from the rear toward the forward end of the coupler.

19 is a set-screw inserted into a suitably threaded orifice in the side of the knuckle pin 2, and having the end thereof projecting into the opening 11, and it may be here mentioned that the knuckle pin is secured from rotation in the regular car coupler, thus the screw 19 limits the rotation of the automatic coupler around the lower end of the knuckle pin, and also limits the vertical movement of said automatic coupler.

20 and 21 are plates secured in any desired manner to the angularly offset portion 7 of the front face of the coupler, and covering the opening of the cored passage 13 therethrough, said plates having the orifices 22 and 23 therethrough.

24 is a rubber bushing fitting the orifices 22 and 23, and having the outwardly extending peripheral flange 25, which is clamped between the plates 20 and 21, whereby the ends of the rubber bushing 24 project one slightly on the inside of the plate 22, and the other slightly on the outside of the plate 23, and it may be here mentioned that the rubber bushing with or without the plates between which it is secured, may be readily removed and renewed when desired.

26 is a valve stem having the offset crank-shaped lower end 27 extending substantially across the recess 12, the vertical portion of said stem extending upwardly from the recess, through a suitable vertical orifice 28, into and through the cored passage 13 on the forward side thereof and immediately next the face plate 20, the upper extremity of said stem extending on into a suitable orifice 29 in the coupler body at the top of the cored passage 13.

30 is a valve blade fixedly mounted at one end thereof on the valve stem 26 where it extends through the cored passage 13, said valve blade extending behind the plate 20 over the opening therethrough, and seating upon the inner end of the rubber bushing 24.

31 is a valve rod having the eye 32 formed at one end thereof and encircling the knuckle pin within the recess 12, said valve rod extending along said recess toward the forward end of the coupler, and having the outer end thereof bent at right angles toward the back of the coupler, and terminating in the hook 33.

34 is a staple formed with a long straight section extending the length of the groove 3 in the knuckle pin 2, and having the inwardly turned staple ends thereof inserted in the recesses 4 at each end of said groove 3, whereby the straight portion of said

staple stands clear of the bed of the groove throughout the length thereof.

35 is a coil spring having the inner end thereof looped about the straight portion of the staple 34, whereby it may slide freely up and down the length of the staple with any vertical movement of the coupler, said coil-spring encircling the knuckle pin 2 within the recess 12 of the coupler, and having the outer end thereof caught onto the crank 75 end of the valve stem 26.

The coil-spring 35 has a double function, namely, its position about the knuckle pin, and the manner in which it is secured at one end thereof to the same turns the coupler 80 about the pin to the position shown in Figs. 1 and 3, that is, with the set-screw 19 against the side of the opening 11 next to the front face of the coupler, and also the said spring draws on the crank end of the valve stem 26 85 to turn the valve 28 into position against the rubber bushing 24.

36 is a bottom plate suitably secured over the entire under side of the coupler, and enclosing the recess 12 with the several parts 90 therein contained as hereinbefore described, said plate however having the slot 37 therethrough registering with the slot 9 to admit of the movement of the coupler on the knuckle pin 2 as hereinbefore described. 95

38 is a socket on the front face of the coupler, and shown in the accompanying drawings as formed from a plate of metal bent into substantially pyramidal shape, said plate having the flanges 39 firmly screwed 100 or otherwise fastened to the coupler, whereby the flaring portion of the socket faces toward the outer and tapered end 8 of the coupler, and further has the opening 40 through which the extreme end of the tapered projection or beak of another coupler may project 105 slightly when interlocked therewith, as hereinafter fully described.

41 is a nipple screwed into the correspondingly threaded opening in the back of the 110 coupler leading to the cored passage 13, said nipple having the regular air or steam conduit hose of the train line connected thereto, whereby the coupler is permitted freedom of movement.

The coupler has been described in the foregoing specification in its normal position before meeting and interlocking with another coupler, that is, in its forward position on the knuckle pin 2, and projecting angularly to present both the beak and the socket toward the front as shown in dotted lines in Fig. 2. It will also be understood that in this position the valve in the cored passage is in its closed position. 115

Upon the meeting of two cars for coupling purposes, the beaks of the couplers, projecting angularly forward as they do and on reverse sides, will take into the sockets of the 130 opposite couplers, and be guided up the in-

cline side of the socket until the extreme ends thereof project slightly through the openings in the apices of the sockets, as shown in full lines in Fig. 2, such being the 5 position when the regular car couplers are united.

The action of the coupler beaks entering the sockets not only assures the proper alinement and registration of the front faces, but 10 of necessity turns each of the couplers on the knuckle pins 2 against the action of the coil spring, until the meeting faces are parallel one with the other, and coincidently the couplers are forced backwardly along 15 the slots 9 on the knuckle pins 2 against the action of the spiral springs 18, whereby the rubber gaskets on the angularly offset portions 7 of the front faces are brought firmly into register one with the other, effecting a 20 tight joint. The forcing back of each coupler along the slot 9 on the knuckle pin 2 as above described further carries the valve rod 31 toward the forward end of the coupler, and thereby turns the crank ends 27 of 25 the valve stems to open the valves away from the inside face of the rubber bushings, and thus open the conduit line through the couplers, and the pressure of air or steam passing therethrough will tend to enlarge 30 the rubber bushings, so that they compress firmly end to end, and form an absolutely tight joint.

The regular car couplers while united will of course hold the air couplers firmly one 35 against the other, and any vertical sliding movement which may occur between the regular car couplers will in no manner affect the air couplers, as they are free to move vertically on the knuckle pins as hereinbefore described a sufficient distance to compensate for any such movement of the regular car couplers.

When the regular car couplers are uncoupled it will be readily understood that 45 the automatic air couplers may withdraw one from the other, and immediately an air coupler is in this manner free, it will be actuated by the coil and spiral springs to assume its normal angular and forward position, as described fully in the first of this specification.

It may be here mentioned that to obviate complicity in the drawings, one cored passage has been shown in each air coupler, 55 whereby a single train line may be completed throughout the train. However, if desired two or more train lines may be completed by duplicating the cored passages and extending the valve stem through the same, 60 and mounting the necessary valves thereon. It will further be understood that the nipple secured in the cored passage on the back of the coupler may be replaced by any regular design of air or steam head, to which the air 65 or steam hose provided with a similar head

may be attached for automatic coupling purposes, or may be detached for coupling in the regular manner by hand to an ordinary hose carrying a head.

The many details of construction and arrangement of parts as shown in the accompanying drawings are of course illustrated, and may be modified in many ways without departing from the spirit of my invention.

What I claim as my invention is:

1. In an automatic coupling for air or steam conduit lines, the combination with the car coupler having an elongated knuckle pin extending downwardly therefrom, of a coupling member mounted on said knuckle pin and springheld to an outward angular position and having a valve controlled fluid passage therethrough and a tapered forward portion and a socket formed on the forward face thereof and into which the 85 tapered forward portion of a second coupler extends upon meeting.

2. In an automatic coupling for air or steam conduit lines, the combination with a car coupler, of a knuckle pin secured in said 90 coupler and extending downwardly therebelow and having a longitudinally extending groove, a coupling member having a valve controlled fluid passage therethrough and a tapered beak extension and a socket 95 formed on the forward face thereof and mounted upon said knuckle pin over the longitudinal groove therein, a staple rod secured in said groove, a coil-spring encircling said knuckle pin and having one end 100 thereof looped around said staple rod and the other end thereof secured to said coupling member to exert a radial action upon the same about said knuckle pin, means for limiting the radial movement of said coupling member and means for limiting the 105 vertical movement of said coupling member upon said knuckle pin.

3. In an automatic coupling for air or steam conduit lines, the combination with a 110 car coupler, of a knuckle pin secured in said coupler and extending downwardly therebelow, a coupling member having a fluid passage therethrough and a tapered beak extension and a socket formed on one face 115 thereof and a vertical slot through which said knuckle pin extends, means for spring-holding said coupling member with the knuckle pin at the end of said slot opposite said beak, a flap valve controlling the opening through said fluid passage, a valve stem operatively connected to said flap valve and having a crank formed at the end thereof and a valve rod encircling said knuckle pin and operatively engaging with the crank 120 end of said valve stem to operate said valve upon an endwise movement of said coupling member.

4. In an automatic coupling for air or 130 steam conduit lines, the combination with a

car coupler, of a knuckle pin secured in said coupler and extending downwardly therebelow, a coupling member of substantially rectangular shape having a beak-shaped extension from one end thereof and a socket formed on one side face thereof and a fluid passage therethrough and a vertical slot therethrough and through which said knuckle pin extends and orifices extending from the beak end of said member through to said vertical slot, an arc-shaped plate arranged within said vertical slot and bearing upon one side of said knuckle pin and having guide rods extending therefrom through said orifices, spiral springs encircling said guide rods between said plate and said orifices, means for springholding said coupling member into position radially about said knuckle pin and a valve controlling the opening through said fluid passage and operative upon the endwise movement of said member on said knuckle pin.

5. In an automatic coupling for air or steam conduit lines, the combination with a car coupler having a knuckle pin secured therein and extending downwardly there-

low, of a coupling member of substantially rectangular shape having one side face thereof angularly offset intermediate of the length thereof and a beak extension from one end and a fluid passage therethrough opening into the angularly offset portion of the one side face and a vertical slot through which said knuckle pin extends, a rubber bushing secured over the opening to said fluid passage through said angularly offset face, a flap valve arranged within said fluid passage and closing against the inner face of said bushing, means for flexibly connecting the opposite end of said fluid passage with the train-line of the car and means for permitting a limited movement of said coupling member upon said knuckle pin vertically, radially and lengthwise.

Signed at the city of Calgary, Province of Alberta, Canada, this 31st day of December, 1912.

HANS VIDEBAK.

In presence of—

ALEXANDER B. HACKAY,
CATHERINE F. GORDON.
